CLAIM

The ornamental design for an LED lamp, as shown and described.

DESCRIPTION

FIG. 1 is rear elevational view of an LED lamp showing my new design.

FIG. 2 is a bottom plan view thereof.

FIG. 3 is a front elevational view thereof.

FIG. 4 is a left side elevational view thereof. The right side elevational view is a mirror image of the left side elevational view; and,

FIG. 5 is a front perspective view thereof.
